A. U. BALDWIN

BOX COVER

Filed May 2, 1925

INVENTOR
AMOS U. BALDWIN
BY *Arthur L. Sles*.
ATTY.

UNITED STATES PATENT OFFICE.

AMOS U. BALDWIN, OF NAPA, CALIFORNIA.

BOX COVER.

Application filed May 2, 1925. Serial No. 27,541.

My invention relates to improvements in covers for boxes of the type used for packing berries, fruits, and the like wherein thin wooden strips are bent to form the bottom and the sides of a box or basket, the side portions being held by a metal strip crimped onto the upper edges thereof.

In packing berries, or other products in boxes or baskets of the character mentioned, the top is left entirely open thus permitting dust and dirt to settle upon the top layer of the product and allowing the product to be readily spilled should the box be inadvertently tipped or inverted. My present invention is therefore directed to an improved cover for such boxes or baskets, the primary object being to provide a cover which may be easily applied and which will effectually be held to close the top of the box.

Another object is to provide an improved cover which will permit the berries or other product to extend somewhat above the level of the top of the box without impairing the operativeness of the cover.

A further object is to provide an improved cover which may be used to effectually identify the product and, if desired, the producer.

Another object is to provide a device which will reduce the amount of wrapping and tying necessary when the product is sold to retail trade.

A still further object is to provide a device of the character described which may be manufactured at a very nominal cost and which may be applied with a minimum expenditure of time and labor.

I accomplish these and other objects by means of the device disclosed in the drawings forming a part of the present specification wherein like characters of reference are used to designate similar parts throughout said specification and drawings, and in which

Fig. 1 is a side elevation of a box or basket provided with my improved cover.

Fig. 2 is a plan view of the cover as cut, the figure being drawn upon a somewhat smaller scale.

Fig. 3 is a broken side elevation of the basket and cover as viewed from the side of Fig. 1.

Fig. 4 is a broken plan view of one corner of the cover and basket, the cover being partly broken away and shown in section.

Referring to the drawings the numeral 1 is used to designate in general a box or basket of the type commonly used for packing berries and fruits, said box consisting of two thin strips of wood placed at right angles to each other and having their ends bent to form sides of the box or basket. The sides flare slightly toward the top of the basket and are held by means of a thin metal strip 2 crimped upon the upper edges of the sides in the well known manner. The sides of the box are arranged to be held in slightly spaced relation so that openings 3 are formed along the corners of the box between adjacent edges of the side portions of the box. Slots 4 are formed in the side portions to afford ventilation to the portions of the product packed in the lower portion of the box. The strip 2 forms a continuous band extending entirely around the upper edge of the box and is shaped to form right angles around the corners of the box to define a square.

My improved cover consists of a flat body portion 6 cut from light cardboard or other suitable material of a size and shape adapted to cover the top of the box 1, and provided with extensions 7 and 8 arranged to be folded downwardly to engage the sides of the box 1. The cover is cut as a flat cardboard blank and creased along the edges of the body portion 6 as at 9 whereby the extensions may be readily folded to operative position.

The extensions 7 are formed upon opposite sides of the body portion 6 and are adapted to be moved into engagement with the inside of the adjacent sides of the box. Tabs 10 are formed upon the sides of the extensions 7 in spaced relation to the adjacent edges of the body portion 6, said tabs extending outwardly from the edges of the extension sufficiently to be engaged by the metal strip 2 as hereinafter more fully explained.

The extensions 8 are formed upon the other opposite sides of the body portion 6 and are adapted to be folded downwardly against the outside of the adjacent sides of the box 1. The extensions 8 are provided with tabs 11 formed by oppositely inclined angularly disposed slots 12 cut in the outer edges of the extension at points substantially opposite the slots 4 formed in the sides of the box.

As above mentioned the cover is cut from flat sheet material and is normally shipped and stored in flat condition. In operation the cover is applied to a box 1 by bending 5 the extensions 7 and 8 downwardly along the creases 9 to engage the sides of the box. The extensions 7 are moved to engage the inner sides of the adjacent sides of the box, the extensions and tabs 10 being bent sufficiently 10 to permit said tabs to pass the band 2 and thereafter straightened so as to cause the tabs 10 to extend outwardly through the openings 3 in the corners of the box. The extensions are thus positioned in such manner 15 as to engage the underside of the corner portions of the band 2 and effectually hold the cover upon the box. The tabs are spaced from the edges of the body portion 1 so as to afford a limited sliding movement of the 20 cover relative to the box and to permit the cover to be held in spaced relation above the top of the box so as to permit the fruit to be packed to a point slightly above the level of the top of the box.

25 After the extensions 7 and the tabs 10 have been moved to engage the box as above explained the tabs 8 are bent to engage the outer sides of the adjacent sides of the box. The tabs 11 are then inserted through the 30 slots 4 in the sides of the box 1 as shown in Fig. 3 of the drawings, thereby effectually holding the extensions 8 against the sides of the box, and cooperate with the tabs 10 to hold the cover upon the box.

35 The cover as thus applied and held upon the top of the box effectually retains the product within the box and protects the product from dirt and dust. The cover also serves to protect the upper layers of the 40 fruit or berries from bruising during shipment and facilitates the stacking of the boxes for shipment. If desired the cover may be printed with any appropriate subject matter to identify the product and its 45 grower or packer and thus serve to advertise the goods of a particular individual or firm.

As the cover is effectually retained in position, the amount of wrapping and tying ordinarily required when the product is sold 50 to the retail trade is reduced. Thus where ordinarily a heavy paper wrapper is applied to protect the product and to prevent the spilling or loss of the product, the cover itself serves this purpose and the boxes require little if any wrapping to place them in a deliverable condition. This fact effects a saving which substantially offsets the cost of the covers.

The cover may be made in various sizes to 60 fit the several sizes of boxes used for packing different kinds of berries and fruits. In all cases the extensions and tabs are sufficiently small and flexible to enable the cover to be applied with very little time or effort 65 and the increased cost of packing due to the

applying of the covers is so small as to be negligible in comparison with the advantages derived.

The specific form and arrangement of the several parts of my improved cover may of course 70 be modified in various ways without departing from the spirit of my invention. I therefore do not wish to restrict myself to the specific structure shown but wish to avail myself of all modifications which may 75 fall within the scope of the appended claims.

Having thus described my invention what I claim as new and desire to secure by Letters Patent is,

1. A cover for berry boxes and the like 80 comprising a flat body portion adapted to cover the top of a box having a band at its upper edge for holding the sides of the box; extensions formed upon opposite sides of the body portion and adapted to be folded 85 downwardly into engagement with the adjacent sides of the box; and means formed on the extensions and adapted to engage the underside of the band in openings formed in the corners of the box for normally holding 90 the cover upon the box.

2. A cover for berry boxes and the like comprising a flat body portion adapted to cover the top of a box having a band at its upper edge for holding the sides of the box; 95 extensions formed upon opposite sides of the body portion and adapted to be folded downwardly into engagement with the adjacent sides of the box; and tabs formed upon the sides of the extensions and adapted to 100 extend through openings formed in the corners of the box and to engage the underside of the band for normally holding the cover upon the box.

3. A cover for berry boxes and the like 105 comprising a flat body portion adapted to cover the top of a box having a band at its upper edge for holding the sides of the box; extensions formed upon opposite sides 110 of the body portion and adapted to be folded downwardly into engagement with the adjacent sides of the box; and tabs formed upon the sides of the extensions and adapted to extend through openings formed in the corners of the box and to engage the underside of the band for normally holding the cover upon the box, said tabs being spaced 115 from the adjacent edges of the body portion to permit the cover to be held in spaced relation to the top of the box.

4. A cover for berry boxes and the like comprising a flat body portion adapted to cover the top of a box having a band at its upper edge for holding the sides of the box; extensions formed upon opposite sides 125 of the body portion and adapted to be folded down to be received inside the adjacent sides of the box; and tabs formed upon the sides of the extension in spaced relation to the adjacent edges of the body portion, said tabs 130

being adapted to extend outwardly through openings formed in the corners of the box and to engage the underside of the band for normally holding the cover upon the box 5 and in slightly spaced relation to the top thereof.

5. A cover for berry boxes and the like comprising a flat substantially square body portion adapted to cover the top of a box 10 having a band at its upper edge for holding the sides of the box; extensions formed upon the sides of said body portion and adapted to be folded downwardly into engagement with the sides of the box; and means formed 15 upon the extensions and adapted to engage the underside of the band in openings formed in the box for normally holding the cover upon the box.
6. A cover for berry boxes and the like 20 comprising a flat substantially square body portion adapted to cover the top of a box having a band at its upper edge for holding the sides of the box; extensions formed upon the sides of said body portion and adapted 25 to be folded downwardly into engagement with the sides of the box, two opposite extensions being received inside the adjacent sides and the other two extensions being adapted to engage the outer side of the adjacent 30 sides of the box; and means formed upon the inner extensions and adapted to engage the underside of the band in openings formed in the box for normally holding the cover upon the box.
- 35 7. A cover for berry boxes and the like comprising a flat substantially square body portion adapted to cover the top of a box having a band at its upper edge for holding the sides of the box; extensions formed upon 40 the sides of said body portion and adapted to be folded downwardly into engagement

with the sides of the box, two opposite extensions being received inside the adjacent sides and the other two extensions being folded against the outside of the adjacent 45 sides of the box; tabs formed upon the inner extensions and adapted to extend outwardly through openings formed in the corners of the box and to engage the underside of the band and tabs formed upon the outer 50 edges of the outer extensions to engage slots formed in the sides of the box and co-operating with the first named tabs to normally hold the cover upon the box.

8. A cover for berry boxes and the like 55 comprising a flat substantially square body portion adapted to cover the top of a box having a band at its upper edge for holding the sides of the box; extensions formed upon the sides of said body portion and adapted to 60 be folded into engagement with the sides of the box, two opposite extensions being received inside the adjacent sides and the other two extensions being folded against the outside of the adjacent sides of the box; tabs 65 formed upon the inner extensions and adapted to extend outwardly through openings formed in the corners of the box; and tabs formed upon the outer edges of the outer extensions to engage the underside 70 of the band in slots formed in the sides of the box to normally hold the cover upon the box; said tabs being positioned in spaced relation to the adjacent edges of the body portion to permit a limited sliding movement of the cover relative to the box and to normally hold the cover in spaced relation to the top of the box. 75

In witness whereof I hereunto set my signature.
